UNITED STATES PATENT OFFICE.

GROVER CLEVELAND LOENING, OF BOSTON, MASSACHUSETTS, ASSIGNOR TO STURTEVANT AEROPLANE COMPANY, OF JAMAICA PLAIN, MASSACHUSETTS, A CORPORATION OF MASSACHUSETTS.

AEROPLANE.

1,283,828.

Specification of Letters Patent.

Patented Nov. 5, 1918.

Application filed October 31, 1916. Serial No. 128,789.

To all whom it may concern:

Be it known that I, GROVER CLEVELAND LOENING, a citizen of the United States, residing at Boston, in the county of Suffolk 5 and State of Massachusetts, have invented an Improvement in Aeroplanes, of which the following description, in connection with the accompanying drawings, is a specification, like characters on the drawings representing like parts.

The invention to be hereinafter described relates to aeroplanes, and more particularly to an improved radiator cooling system for the engine of an aeroplane.

15 Heretofore, the radiator has been located directly in front of the engine, back of and in axial alignment with the propeller where it is partially shielded by the latter and out of range of the effective air-cooling currents; or it has been located at a side of the engine where it is subject to objectionable vibrations, presents excessive head resistance, is difficult to support, and is in the way of the pilot of the aeroplane.

25 The present invention aims to overcome the above and other objections to former constructions. To accomplish this, one object of the invention is to construct and arrange the radiator to reduce head resistance to the air. Another object is to increase the cooling efficiency of the radiator. Another object is to locate the radiator within the range of the energetic air currents developed by the propeller blades.

35 Another object is to eliminate the vibrations of the radiator. Another object is to construct and arrange the radiator to prevent its obstructing the vision of the pilot. Still another object is to promote the circulation 40 of the cooling water through the system.

The character of the invention may be best understood by reference to the following description of the embodiments thereof shown in the accompanying drawings, 45 wherein:

Figure 1 is a front elevation of a portion of an aeroplane equipped with a radiator engine cooling system embodying the invention;

50 Fig. 2 is a perspective view on an enlarged scale, of the parts shown in Fig. 1;

Fig. 3 is another perspective view of the radiator showing the piping connections therefor; and

55 Fig. 4 is a front elevation of an aero-

plane and radiator construction, somewhat different from that shown in Figs. 1 to 3.

Referring to the drawings: 1 and 3 in Fig. 1 designate the upper and lower main sustaining planes of an aeroplane of the seaplane type. These planes may be connected by vertical struts 5, stiffened by diagonal guy wires 7. Pontoons 9 are provided beneath the planes for supporting the machine upon water, and may be connected to the lower main plane by struts 11 stiffened by diagonal stays 13. A body 15 mounted centrally above the lower plane receives the engine which drives the propeller 17 and contains the cock-pit for the accommodation of the pilot of the aeroplane, and passengers. The engine is provided with a water chamber for cooling the same, of usual construction, and therefore unnecessary to illustrate herein.

Having described the general construction of the machine, next will be described the improved radiator cooling system embodying the invention. The radiator comprises an upper header 19 (Figs. 2 and 3), 30 in the present instance, within the plane of the upper main sustaining plane, and preferably fitted into a recess 21 in the advancing edge of said plane. This header 19 may be shaped to conform to the contour of said 35 plane, and constitute, in effect, a part thereof.

A hollow U-shaped frame 23 may depend from the said header and contain the usual comb 25 providing an extended surface, 40 rificulated to permit the effective cooling action of the air thereon. A cap 26 at the top of the header, permits the introduction of water therein.

In the present instance of the invention, 45 the radiator is shown provided with piping for a V engine, comprising two groups of cylinders. The hot water may be conducted from the jackets for the groups by inlet pipes 27 extending upward through the 100 cowl of the body in front of the radiator comb and entering the under wall of an advance overhanging edge of the header 19, as will be clearly understood from Figs. 2 and 3.

The hot water thus entering the header 50 may be distributed by the latter to the comb and gravitate downward through the comb and be cooled in its transit therethrough. The cooled water is conducted therefrom 110

back to the engine jackets through the outlet pipes 29 having their upper ends entered into the base of the radiator frame. These water circulation pipes may be in sections 5 connected by rubber unions 31 clamped thereto for preventing transmission of engine vibrations to the radiator.

To secure the radiator in position, its header may have angle brackets 33, Fig. 2, 10 on the rear edge thereof bolted to brackets 35 on the main plane, and its U frame may have brackets 37, Fig. 3, on the base thereof, connected by the clips 39 with the upwardly converging struts 41 having their 15 lower ends secured to the body fuselage at the rear of the cowl, and their upper ends secured to the upper main sustaining plane. These struts may serve as a backing for the radiator and cooperate with the upper main 20 plane to hold the radiator rigidly in position without vibration.

In Fig. 4 is shown an aeroplane of similar construction, but somewhat different proportions from the aeroplane shown in 25 Figs. 1 to 3, and equipped with a radiator 43 similar to the one first described, but with the exception that it is longer, narrower, projects a shorter distance beneath the upper main plane, and its inlet and outlet 30 pipes 45 and 47 project vertically upward in registration with the struts 51 extending between the fuselage and the upper main plane. This tandem arrangement of the struts and pipes reduces head resistance to 35 the air, provides a strong, compact construction, and forms a desirable stream line construction.

There are important advantages in the radiator constructed and arranged as 40 described.

The upper header of the radiator essentially must have a substantial front area in order to supply and distribute the water to the comb beneath it, but this area, instead 45 of offering head resistance, constitutes, in effect, a part of the main sustaining plane, and serves the dual function of accommodating water for the radiator, and contributing to the support of the aeroplane. The U- 50 frame containing the comb presents merely a very narrow edge to the air, and does not offer material head resistance. Thus, substantially the only portion of the radiator which is exposed to the air currents, is the 55 comb portion of the radiator, but this portion being reticulated, permits the air to readily pass therethrough. Therefore, a radiator is provided which is highly effective in cooling the water, but without material 60 head resistance to the air.

Since the radiator is long and narrow, it may lie closely adjacent to the under surface of the upper main plane in a position where it can receive and be effectively cooled by the 65 energetic air stream compressed by said

plane. The advance edge of the radiator header projecting somewhat beyond the comb, desirably contributes to the compression and direction of the air stream to the comb.

The long, narrow radiator projecting merely a slight distance beneath the upper main plane, is well up out of the way of the pilot and does not offer any obstruction to his view. Since the header is located well 70 up a substantial distance from the engine, with pipes of substantial length connecting them, the hot water will naturally tend to rise in the inlet pipes, and the cold water will naturally tend to fall in the outlet pipes. 75 Thus, there is provided a thermosiphon effect which will desirably assist the pump in the system in maintaining the circulation of water through the system. 80

The fitting of the radiator head into the 85 recess of the main plane and the securing of the U-frame to the stiff struts back of the radiator, effectively prevents vibrations thereof.

What is claimed is:—

1. In an aeroplane, the combination with 90 a main sustaining plane, of a radiator comprising a header and a reticulated portion, said header being formed to conform to and constitute a part of said plane.

2. In an aeroplane, the combination with 95 a main sustaining plane, of a radiator comprising a header within said plane and an elongated reticulated portion projecting slightly beneath said plane and exposed to 100 the air stream thereat.

3. In an aeroplane, the combination with 105 a main sustaining plane, of an engine cooling system including a radiator having a header forming a part of said plane and a reticulated portion projecting beneath said plane, a water inlet pipe communicating with said header, and a water outlet pipe communicating with said reticulated portion.

4. In an aeroplane, the combination with 110 a main sustaining plane and a strut therefor, of an engine cooling system including a radiator having a header forming a part of said plane, and an air exposed cooling 115 portion projecting beyond said plane, and water circulation pipes communicating with said radiator and registering with said strut to diminish head resistance to the air.

5. In an aeroplane, the combination with 120 a main sustaining plane, of an engine support, struts extending between said plane and support, a cooling system for the engine including a radiator having a header in the plane of said sustaining plane, an air exposed cooling portion projecting beyond said plane, and water circulation pipes communicating with said radiator and registering with said struts.

6. In an aeroplane, the combination with 125

- upper and lower main sustaining planes, of an engine cooling system including a radiator having a header in the plane of one of said sustaining planes; an air exposed cooling portion projecting beyond said plane, struts connected to the latter, means for securing the radiator to said struts, and piping registering with said struts for conducting water to and from said radiator.
- 5 7. In an aeroplane, the combination with a main sustaining plane, of an engine cooling system including a radiator having an air cooling portion projecting beneath said plane, and a header formed to conform to the contour of said plane and presenting a plane section for compressing and directing a cooling air stream to said air cooling portion.
- 10 8. In an aeroplane, the combination with a main sustaining plane having a recess therein, of a radiator comprising a header with a reticulated portion depending therefrom, said header being mounted in said re-
- cess and having an advance edge portion projecting beyond said reticulated portion 25 to deflect the air thereto, and means to conduct water to and from the radiator.
9. In an aeroplane, the combination with a main sustaining plane having a recess therein, of a radiator comprising a header 30 set into said recess, a hollow frame depending from said header and plane, a hollow reticulated structure mounted in said frame, and means to conduct water to and from said radiator.
- 15 10. In an aeroplane, the combination with a main sustaining plane having a recess therein, of a radiator comprising a header set into said recess and secured to said plane, a reticulated portion projecting from said 40 header and plane and exposed to the air stream passing said plane, and means to conduct water to and from said radiator.

In testimony whereof, I have signed my name to this specification.

GROVER CLEVELAND LOENING.
